KNIFE SHARPENER

Joseph Urban, Detroit, Mich.

Application October 30, 1944, Serial No. 560,968

2 Claims. (Cl. 51—214)

1

This invention relates to a knife sharpener and has to do particularly with a sharpener which can be advantageously used for home purposes.

A general object of the invention is to provide a novel and efficient sharpener construction which will properly sharpen a knife blade and which can be used not only with safety but can be operated by those unskilled in the art of sharpening and putting an edge upon a blade. An abrading element is employed and the device may be supplied with a number of abrading elements with different cutting characteristics ranging from a relatively coarse file to a fine cutting stone.

The accompanying drawing illustrates a sharpener constructed in accordance with the invention. In the drawing:

Fig. 1 is a top plan view of the device.

Fig. 2 is a sectional view taken substantially on line 2—2 of Fig. 1.

Fig. 3 is a sectional view taken substantially on line 3—3 of Fig. 2.

The sharpener takes the form of a body member 1 which may have a gripping or handle part 2 which can be easily held by one hand and a wider base portion 3. The wider base portion provides suitable size and strength for the holding of the abrading element and provides a base area so that the device may be stored in an upright position.

The body is formed with a hole or passage 5 therein and a slot 6 which intersects the passage. For convenience of manufacture the hole 5 may pass entirely through the body with its lower end illustrated at 7.

The body is provided with a sort of chamber or cavity at the bottom of the slot 6 which is defined by an inclined bottom wall 10, the inclination of which is downwardly in a direction toward the opening of the slot 6. The back wall 11 and the front wall 12 of the cavity are inclined preferably so that they are at right angles to the inclined bottom 10. This cavity is for the reception of an abrading element 15 which can be slipped into and out of position through the open sides of the cavity. The disposition of the bottom wall 10 at an angle and the cooperating angle on the walls 11 and 12 provide an arrangement for the reception of an abrading element conventionally made of rectangular cross section. Accordingly, the abrading element fits snugly in the cavity.

If desired, the abrading element may be permanently located or it may be arranged so that it can be removed so that the abrading element

may be replaced or one having different cutting characteristics substituted therefor.

Means are provided for applying pressure to the blade of a knife and this takes the form of a suitable rod or post 16 slidably mounted in the hole 5 and advantageously provided with a suitable cap or head piece 17. On the opposite end of the rod and lying in the slot 6 is a blade engaging piece 18 suitably attached to the rod. 10 The pressure piece 18 may advantageously be mounted on the rod 16 in an eccentric manner so that its four edges 20, 21, 22 and 23 are located at different distances from the center of the post.

15 In the operation of the device a knife blade, which may be termed the work piece, as shown at W, is passed into the slot with its cutting edge positioned toward the abrading element. It will be noted that the slot 6 is materially wider than the thickness of the blade. The blade is moved into position under the pressure member 18. As a result, one side of the cutting edge of the blade is engaged by the abrading element and the other side of the blade is engaged by the 20 pressure piece 18. In this position the knife blade is reciprocated back and forth in a direction paralleling the cutting edge and thus the cutting edge is sharpened by the abrading action. Suitable pressure may be applied by a thumb or 25 finger to the top of the post 17. This will be regulated as desired. After one edge of the knife has been subjected to the sharpening action the blade may be reversed so that the opposite edge is placed next to the abrading element. The 30 eccentric disposition of the pressure piece 18 makes it feasible to apply the knife edge with pressure at various locations on the cutting element. The edge 20 may apply the pressure nearest the lower edge of the abrading element 35 while the edge 23 will extend well back toward the bottom of the slot 6 to apply pressure at the corresponding part of the abrading element. This increases the life of the abrading element 40 while the edge 21 and 22 may apply pressure to the intermediate portions of the element. As the blade is reciprocated the body thereof may rest upon the surface 25 of the slot 6, while the edge engages the angularly positioned stone. The angle of the abrading element 45 is preferably such as to provide an efficient sharpening and edging of the cutting edge of the knife.

I claim:

1. A knife sharpener comprising, an elongated

3

body of handle-like form adapted to be gripped in the hand of the user, and having an extending end part beyond the portion adapted to be so gripped, said end part having a slot extending partially therethrough transverse to the length of the body, said slot having a chamber in its innermost portion extending through the body with the chamber having an inclined bottom wall, an abrading stone in the chamber and adapted to be pushed into position through the open end of the chamber, said abrading stone having its lower surface seating upon the inclined bottom and having its upper surface extending angularly in the direction transverse of the slot, whereby the edge of a knife blade passed into the slot angularly engages the surface of the abrading stone, said body having an opening extending lengthwise through the handle part and opening into the slot; a rod member positioned and freely slideable in the opening, and a pressure piece connected to the rod and located in the slot, the exposed end of the rod adapted to be pressed to urge the pressure member against the side of the knife blade to in turn apply the knife blade to the cutting stone with pressure.

2. A knife sharpener comprising, an elongated body of handle-like form adapted to be gripped in the hand of the user, and having an extending end part beyond the portion adapted to be so

4

gripped, said end part having a slot extending partially therethrough transverse to the length of the body, said slot having a chamber in its innermost portion extending through the body with the chamber having an inclined bottom wall, an abrading stone in the chamber and adapted to be pushed into position through the open end of the chamber, said abrading stone having its lower surface seating upon the inclined bottom and having its upper surface extending angularly in the direction transverse of the slot, whereby the edge of a knife blade passed into the slot angularly engages the surface of the abrading stone, said body having an opening extending lengthwise through the handle part and opening into the slot, a rod member positioned and freely slideable in the opening, a pressure piece connected to the rod and located in the slot, the exposed end of the rod adapted to be pressed to urge the pressure member against the side of the knife blade to in turn apply the knife blade to the cutting stone with pressure, said pressure member being eccentrically connected to the rod whereby the rod may be turned in the opening so that it may be applied to the side of the knife blade with the cutting edge of the knife blade engaging the abrading stone at different locations across the width thereof.
